UNITED STATES PATENT OFFICE.

CHARLES E. GOODWIN, OF SEATTLE, WASHINGTON.

MECHANICAL TOY INSECT GUN.

1,425,249.

Specification of Letters Patent. Patented Aug. 8, 1922.

Application filed September 6, 1921. Serial No. 498,786.

To all whom it may concern:

Be it known that I, CHARLES E. GOODWIN, a citizen of the United States, residing at Seattle, in the county of King and State of Washington, have invented a new and useful Mechanical Toy Insect Gun, of which the following is a specification.

My invention relates to improvements in mechanical toy insect guns, and an object of 10 my invention is to provide an insect gun which, by reason of its attractive features, will afford the user sufficient amusement to hold his attention and also act as an incentive to him in ridding the home of flies and 15 other germ carrying insects.

Other objects are to provide an insect gun which is harmless to the user, which will not mar or blemish the furniture, and which will kill insects without mashing them on 20 the house furnishings.

Still further objects are to provide an insect gun which is reliable and efficient in operation, simple and durable in construction, and which may be manufactured at comparatively small cost.

With the above and other objects in view which will appear as the description proceeds the invention consists of the novel construction, adaptation, arrangement and combination of parts hereinafter described and claimed.

I accomplish these objects by devices illustrated in the accompanying drawings, wherein:

35 Figure 1 is a view in side elevation of a toy insect gun embodying the features of my invention, with the elastic drawn and the trigger cocked to normal position for shooting;

40 Fig. 2 is a view in central longitudinal vertical section of same with parts in elevation and showing the positions of the triggers etc. at the instant the elastic is released and also showing the sliding barrel member 45 in a slightly extended position, and;

Fig. 3 is a view in side elevation of a modified form of my invention with certain parts shown in central longitudinal vertical section.

50 Referring to the drawings, throughout which like reference numerals designate like parts, the numeral 10 designates the gun-stock which is integrally formed with the barrel 11.

55 The underside of the barrel 11 is provided with a depending shoulder 12 against which

a sliding barrel member 13 is arranged to abut when same is in the contracted position. Said sliding barrel is provided with a boss 14 which is used as a handgrip in manipulating said barrel member. A bracket band 15 is passed around the barrel 11 and secured at its underside to the boss 14. A similar bracket band 16 is passed around the sliding barrel member 13 and secured at its upper side to the barrel 11. Said bracket bands serve to retain the sliding barrel member 13 in alignment with the barrel 11 and also serve to limit the outward movement of said sliding barrel when brought in contact with 70 each other.

A central longitudinal groove 17 is provided in the underside of the barrel 11 extending substantially from the shoulder 12 to the juncture of said barrel and the stock 75 10. A flat spring 18 is arranged to bridge across said groove and is normally held flush against the underside of said barrel by a bell 19 which is held thereagainst by a bolt 20 secured through said barrel as clearly 80 shown in the drawings.

A hole 21 is provided through the barrel 11 and a trigger 22, which is shaped substantially in the form of the letter S, is normally held in a cocked position within the groove 85 17 by the flat spring 18 with its upper or hammer end 23 projecting through said hole 21 slightly above said barrel and its lower or finger end 24 projecting below said barrel as shown in Fig. 1.

An opening 25 is provided through the barrel 11 and a clapper 26 is pivotally mounted within said opening with its upper end projecting slightly above said barrel and its lower end projecting sufficiently below said pivotal point and barrel so that same will normally gravitate to a substantially upright position. A small leaf spring 27 is secured to the upper side of said barrel with its free end projecting downwardly 100 within said opening 25 to a point just clear of the clapper 26 when same is in its normal position.

An elastic band 28, having a tassel 29 fastened to one of its ends, is secured at its opposite end to the outer end of the barrel member 13 by a suitable fastening 30. The tassel 29 is preferably made of leather, hemp or fabric and is soft enough to prevent injury to the user yet of sufficient body to destroy an insect upon functional contact with same.

From Fig. 1 of the drawings it will be understood that the positions of the trigger, clapper, etc., are always held normally cocked and ready for action and all that is necessary is to draw the elastic band back each time and place same over the upper end 23 of the trigger 22. By drawing the lower end 24 back until its middle bent portion presses downwardly against the spring 18 and its other middle bent portion presses upwardly against the underside of the barrel groove 17, the upper end 23 of said trigger will be drawn downwardly until it releases the elastic band 28, carrying the tassel 29, which will immediately spring forward. Referring to Fig. 2 of the drawings, it will be seen that the loop of said band will strike the upper end of the clapper 26, in passing, and will cause the lower end of said clapper to strike the bell 19. The upper end of said clapper will be drawn against the leaf spring 27, and, as said band passes over, said leaf spring will immediately draw said clapper away from said bell and thus prevent any interference with its resonance. The springs 18 and 27, when released, will automatically cause the trigger 22 and clapper 26 to assume their normal positions in readiness for another operation. It will be obvious that the sliding barrel member 13 may be pushed outward to extend the length of the gun barrel as a whole when it is desired to increase the tension of the elastic band 28.

In the modified form of my invention shown in Fig. 3 of the drawings, a rod 31, preferably made of wire, is substituted for the sliding barrel member 13, while the groove 17 is extended to a shoulder 32. Said rod is passed through a central bore 33 and bent downwardly at its inner end and fastened in the boss 14. The outer end of said rod terminates in a loop 34 through which the outer end of the elastic band 28 is fastened and it will be apparent that said band may be extended in like manner, while the other features of the modified form are similar to the preferred construction shown in Figs. 1 and 2.

The toy is usually painted in bright alluring colors, and together with the novel feature of ringing the bell at each operation, is designed to attract and amuse a child in particular to the extent that he will employ same in the useful purpose of ridding the home of the filthy common house fly,

the poisonous mosquito, or other objectionable insects.

From the foregoing description taken in connection with the accompanying drawings, the form of construction and method of operation of my insect gun will be readily apparent to those skilled in the art to which the invention relates, and, while I have described the principle of operation together with the device which I now consider to be the best embodiment thereof, it will be understood that the device shown is merely illustrative and that such changes may be resorted to as are within the scope and spirit of the invention.

What I claim is:

1. A mechanical toy insect gun comprising a stock and barrel, an extension barrel member slidably secured to said barrel, an elastic secured at its outer end to said extension barrel member, a tassel secured to the inner end of said elastic, and trigger means for releasing the tassel end of said elastic when under tension to cause same to spring forward.

2. A mechanical toy insect gun comprising a stock and barrel, an extension barrel member slidably secured to said barrel, a bell secured to said gun, a clapper secured to said barrel adjacent said bell, an elastic secured at its outer end to said extension barrel member, a tassel secured to the inner end of said elastic, and trigger means adapted to release the inner tassel end of said elastic when under tension to allow same to spring forward and to cause said clapper to strike said bell.

3. A mechanical toy insect gun comprising a stock and barrel, an extension barrel member slidably secured to said barrel, a bell secured to said gun, a clapper pivotally secured to said barrel adjacent said bell, an elastic band secured at its outer end to said extension barrel member, a tassel secured to the inner end of said elastic band, trigger means adapted to release the inner tassel end of said elastic band when caught over same under tension to permit said band to spring forward and to cause said clapper to strike said bell, spring means adapted to withdraw said clapper from said bell, and spring means adapted to functionally retain said trigger means in a normally cocked position.

CHARLES E. GOODWIN.
